FOUNTAIN PEN

Herman Baron, San Salvador, El Salvador

Application June 23, 1937, Serial No. 149,976

4 Claims. (Cl. 120—47)

The invention relates to a writing pen and more especially to a fountain pen.

The primary object of the invention is the provision of a pen of this character, wherein the barrel is fitted with a novel form of pump so as to enable the quick and convenient filling of the pen with ink and such pump is a built-in unit of the pen.

Another object of the invention is the provision of a pen of this character, wherein the pump unit includes an extensible one-stroke stem which on the retracting of the same will be confined or concealed within the barrel of the pen and is readily accessible for the operation of the unit to fill the pen with ink by a single stroke action.

A further object of the invention is the provision of a pen of this character, which is simple in its construction, thoroughly reliable and effective in operation, susceptible of filling with ink through a single stroke action in the operation of the pump unit, durable, and inexpensive to manufacture.

With these and other objects in view, the invention consists in the features of construction, combination and arrangement of parts as will be hereinafter more fully described, illustrated in the accompanying drawing, which discloses the preferred embodiment of the invention and pointed out in the claims hereunto appended.

In the accompanying drawing:

Figure 1 is a side elevation of a pen partly in section constructed in accordance with the invention.

Figure 2 is a fragmentary vertical longitudinal sectional view showing the stem of the pumping unit extended.

Figure 3 is a view similar to Figure 2 showing the pumping unit in position for the filling of the barrel of the pen.

Figure 4 is an exploded perspective view of the extensible stem parts disassembled.

Figure 5 is a sectional view on the line 5—5 of Figure 1 looking in the direction of the arrows.

Similar reference characters indicate corresponding parts throughout the several views in the drawing.

Referring to the drawing in detail, the pen constituting the present invention comprises a barrel 10 tapered outwardly at one end at 11 and having in this end a pen point 12 in association with an ink feeder (not shown). The barrel 10 provides an ink chamber 13 interiorly thereof and the opposite end of this barrel is normally open and internally threaded at 14 for remov-

ably accommodating a sleeve-like plug 15 carrying a guide cylinder 16, the latter being fixedly held in a center opening 17 provided in said sleeve-like plug 15. This cylinder 16 constitutes a housing for a purpose presently described.

Accommodated within the cylinder 16 are the inner and outer telescopically fitted stem sections 18 and 19, respectively. The section 19 slidably telescopes over the section 18 and is provided with a bayonet slot 20 longitudinally disposed therein for accommodating a latching lug 21 on the section 18. Thus the section 19 can be extended on the section 18 and both sections 18 and 19 latched in the extended relation thereof.

The plug 15 is formed with a reduced inner end 22 which is accommodated within the open end of an expansible resilient bag 23. This bag fitted over the reduced end 22 is made fast and sealed concentrically about said reduced end by a clamping ring 24. The section 18 of the stem is slidable through a guide opening 25 centrally in the inner end 26 of the cylinder 16 and this section has separably connected thereto at its innermost end a half spherical head 27 which is accommodated within the bag 23 at its inner closed rounded end 28 to avoid damage thereto under expansion of said bag. The section 19 snugly fits within the cylinder 16 and when latched with the section 18 after extension of the section 19 thereon through a single stroke of the stem for expansion of the bag 23 the barrel 10 of the pen will be filled with ink in that the contracting of the said bag within the barrel 10 effects suction of ink through the feeder end 11 for the filling of the ink chamber 13 within said barrel. The section 19 at its outer end has fitted therewith a combined cap and hand knob 29 which enables manual manipulation of the stem for single stroke operation thereof and for the extending of the section 19 of said stem as well as the confinement of this section 19 within the cylinder 16. When the section 19 is confined within the cylinder 16 and the section 18 has become telescoped within the section 19, the cap 29 will effect a closure for the end 14 of the barrel 10.

Normally the section 18 is telescoped within the section 19 of the stem and the latter is pushed inwardly of the cylinder 16 for confinement therein. Now when it is desired to draw ink into the chamber 13 constituted by the barrel 10, an operator or user of the latter pulls the section 19 outwardly of the cylinder 16 and thereafter

latches the cylinder in the extended position with relation to the section 18 of the stem. By forcing these latched sections 18 and 19 with each other inwardly of the cylinder 16, the bag 23 will be 5 expanded and when the latter contracts through inherent elasticity or resiliency a suction will be set up in the chamber 13 so that ink can be drawn into the barrel 10 for the filling of the pen. Thereafter the section 18 of the stem will have 10 moved into the cylinder 16 and it is required that the operator or user pushes the section 19 into the cylinder 16 for confinement therein with the cap 29 closing the end 14 of the barrel 10 of the pen. The pen is now filled with ink and ready 15 for use in the usual well-known manner.

15 What is claimed is:

1. In a pen of the character described, a barrel forming an ink chamber, a plug firmly but removably supported in an opening formed in said barrel, an extensible stem slidably fitting in an opening formed in the plug, a substantially stationary cylinder carried by and substantially fixedly mounted on the plug interiorly of the barrel and adapted to accommodate the extensible 20 stem when in contracted condition, and an inherently elastic bag interiorly of the barrel, substantially fixedly connected to the plug and expanded by the said stem when extended and actuated.
2. In a pen of the character described, a barrel forming an ink chamber, a plug firmly but removably supported in an opening formed in said barrel, an extensible stem slidably fitting in an opening formed in the plug, a substantially stationary cylinder carried by and substantially fixedly mounted on the plug interiorly of the barrel and adapted to accommodate the extensible stem when contracted therein, an inherently elastic bag interiorly of the barrel, substantially fixedly 25 connected to the plug and expanded by the said 30

stem when extended and actuated, and means for latching the stem extended.

3. In a pen of the character described, a barrel forming an ink chamber, a plug firmly but removably supported in an opening formed in said 5 barrel, an extensible stem slidably fitting in an opening formed in the plug, a substantially stationary cylinder carried by the plug interiorly of the barrel and adapted to accommodate the extensible stem when contracted therein, an inherently elastic bag interiorly of the barrel, substantially fixedly connected to the plug and expanded by the said stem when extended and actuated, means for latching the stem extended, and a cap carried at the outer end of the extensible 10 stem for the barrel.

4. In a fountain pen of the type described the combination including a fluid reservoir, means for at least assisting in the filling of said reservoir comprising a substantially cylindrical plug, firmly but removably seated in an opening formed in said reservoir, and having a substantially coaxial opening formed therein; an essentially cylindrical hollow sheath-like guide member relatively fixedly mounted on said plug positioned coaxial 20 with said opening formed therein; a composite extensible plunger member positioned within said guide member comprising a plurality of concentric telescoping tubes adapted to be engaged with each other when in extended position, a substantially hemispherical head carried on and fixedly secured to the end portion of said plunger normally positioned within said reservoir, said head being adapted to rest upon the end of said guide member furthest from said plug; and a substantially cylindrical sac, 25 30 closed at one end, enveloping said head and guide member and fixedly secured at the open thereof to said plug.
